UNITED STATES PATENT OFFICE.

JACOB D. ZEISLOFT, OF FOSTER, PENNSYLVANIA.

COAL-JIG.

SPECIFICATION forming part of Letters Patent No. 437,743, dated October 7, 1890.

Application filed January 7, 1889. Serial No. 295,701. (No model.)

To all whom it may concern:

Be it known that I, JACOB D. ZEISLOFT, of Foster township, county of Luzerne, in the State of Pennsylvania, a citizen of the United States, have invented certain new and useful Improvements in Coal-Jigs, of which the following is a specification.

My invention relates to coal jigs or washers employed for separating slate from coal at the mines by washing with a strong upward and intermittent current of water, the water being actuated by a movable plunger which forces the water up through the coal and slate and separates them, holding the coal in suspension, while the slate and other extraneous matters fall down through the perforations or openings in the bottom.

The objects of my invention are to prevent the great waste of water and effect a better separation by improving the construction of the apparatus; and to these ends I close the end of the tank, formerly left open, to prevent the free running out of the water with the coal and retain a large portion of it in the tank to be used again. I slope the bottom of the washing-chamber from the center downward to the sides, so as to throw the greatest quantity of the coal and slate adjacent to the sides in order that the coal may be readily thrown over into the elevation boxes, and I provide the washing-chamber with an additional floor depressed below the main floor to catch the heavy lumps held back by the fenders.

My invention consists in the several novel features of construction and operation hereinafter more fully described, and set forth in the claims annexed.

The invention is constructed as follows, reference being had to the accompanying drawings, in which—

Figure 1 is a plan view. Fig. 2 is a vertical longitudinal section. Fig. 3 is a vertical section on the line 3 3, Figs. 1 and 2. Fig. 4 is a section on the line 4 4, Figs. 1 and 2. Fig. 5 is a transverse vertical section through the chamber 11. Fig. 6 is a like view through chamber 13.

A is the tank, provided with a vertical transverse wall 1, extending nearly to the bottom and forming one side of the piston-

chamber, and being parallel to the ends 2 and at right angles to the sides 3 and 4.

5 is a frame-work supported at one end upon the wall 1, and at the other upon the partition 6. The frame-work carries the bottom 7, inclined each way from the center downward to the sides and provided with interstices or large perforations 8, and 9 is a secondary double-inclined bottom at the end 60 of the bottom 7, lying in planes below those of the sections of the main bottom.

B is a plunger-piston operated vertically and forcing water from the chamber 10 through under the wall 1 and upward through the bottom 7.

A partition 6 rises vertically from the bottom 9, or it may rise from the bottom of the tank, and is provided with a fender 11, projecting inwardly, substantially as shown, and 70 creating a chamber 13 between this partition and the front 12 of the tank, and this chamber is also provided with a doubly-inclined and perforated bottom 7^a, having perforations 8. Gates 14 are mounted on each side at the 75 lower ends of the bottom 9, through which the slate therein is discharged. The chamber 13 is also provided with gates 15, controlling openings at the bottom and on each side through which the coal mixed with a small 80 quantity of slate is discharged with accompanying water into the elevator box or leg 16, from which it is lifted by the buckets *a* of the rotating elevator C, and from the fact that the buckets are placed diagonally to the periphery of the elevator and consist merely of flat pieces, secured at one edge, as soon as a bucket rises above the top of the side of the elevator-box the coal and slate are discharged into the inclined chutes 17, whence it is discharged 90 through the wicket-gates 18, which are opened and closed by the handle, as shown in Fig. 2.

It will be observed that by the use of the partition 6, which operates as a dam, less water is permitted to enter the chamber 13 than 95 if no such partition were there, and that the fender operates to retard the flow of water and to catch and hold back many pieces of heavy slate which would otherwise be carried over into the chamber 13. It will also be observed that by the use of the flat diagonal buckets I am only compelled to raise the coal 100

and slate to just above the edges of the tank, thereby saving a great amount of power as compared with the cup-buckets. It will also be seen that the doubly-inclined bottoms in 5 the main receptacle and of the slate-receptacle and of the coal-receptacle throw or cause the coal or slate to slide down to the sides and to the gates in the coal and slate chambers.

10 What I claim as my invention, and desire to secure by Letters Patent, is—

The combination of the washing-chamber having the perforated bottom, the means for forcing water up through said bottom, the settling-chamber having the double-inclined 15 perforated bottom located at a lower plane than the bottom of the washing-chamber, gates opening from the lowest portion of the

settling-chamber, the rearwardly-extending guard projecting over the settling-chamber, 20 a supplemental chamber forward of the settling-chamber and separated therefrom by the rearwardly-extending guard, the outlet-gates communicating with the lowest portion of the supplemental chamber, and suitable elevating devices located at the sides of the machine adjoining the ends of said chambers and communicating with said chambers over the end partitions, all substantially as herein set forth. 25

In witness whereof I have hereunto set my hand this 1st day of December, 1888.

JACOB D. ZEISLOFT.

In presence of—

JOHN D. HAYES,

JOHN MILLER.
